(57) **CLAIM**

The ornamental design for an ear cleaning apparatus, as shown and described.

DESCRIPTION

FIG. 1 is a front perspective view of an ear cleaning apparatus in accordance with the present design.

FIG. 2 is a front perspective view of the ear cleaning apparatus of the invention.

FIG. 3 is a left side view of the ear cleaning apparatus of the invention.

FIG. 4 is a right side view of the ear cleaning apparatus of the invention.

FIG. 5 is a rear view of the ear cleaning apparatus of the invention.

FIG. 6 is a top view of the ear cleaning apparatus of the invention; and,

FIG. 7 is a bottom view of the ear cleaning apparatus of the invention.

The broken lines in the figures depict portions of the ear cleaning apparatus that form no part of the claimed design.
